UNITED STATES PATENT OFFICE

JUSTUS J. ROSS, OF HUNTINGTON, WEST VIRGINIA

REENFORCED MINE TIE

Application filed April 23, 1929. Serial No. 357,490.

This invention relates to mine ties and has special reference to means for reenforcing such ties at the points where necessary, namely, where the rails rest on the ties and where the rail fastening clips are mounted.

Mine ties are sold almost entirely by weight and it is obvious that if the weight of the ties can be materially reduced without sacrificing their strength a great saving in the cost of laying tracks in mines will follow. It is therefore an object of the present invention to provide a tie which may be formed of very light metal and reenforce the same where it supports the rails and where the locking clips are mounted.

A further object of the invention resides in the provision of a reenforcing means placed at the point where the pivoted rail clips are riveted to the tie; thus eliminating undue wear on the tie by corrosion and rotation of the clips which would tend to loosen the clips with the consequent danger of freeing the base of the rail and permitting it to turn over.

Other objects and advantages of the invention will be apparent from the following description when taken in connection with the accompanying drawing, in which

Figure 1 is a side elevation of one form of mine tie embodying the present invention.

Figure 2 is a sectional view taken on line 2-2 of Figure 1, showing one of the clips turned to inoperation position.

Figure 3 is a fragmentary, longitudinal section through a modified form of construction.

Figure 4 is a plan view of the structure shown in Figure 3.

Figure 5 is a transverse section through a slightly modified construction of tie; and

Figure 6 is a transverse section through a further modified form of tie.

Referring to the drawings in greater detail and especially to Figures 1 and 2 the numeral 1 designates a piece of metal tubing cut to the proper length and provided with flattened or collapsed ends 2; although if found desirable the tube may be flattened throughout its length. Mounted adjacent the ends of the tube on the flattened portion

thereof and preferably on the top side are reenforcing plates 3. These plates reenforce the tie at the points where the rails are supported, which, as a matter of fact are the only points where strength is required; it being readily apparent that the portion of the tie intermediate the rails has as its sole function to maintain the proper gauge between the rails.

The plates 3 are secured to the tie proper by means of rivets 4 and these rivets also serve as a means for pivoting the rail clips 5. This feature of mounting the rail clips or clamps on a reenforcing plate is also of considerable importance for the reason that where pivoted clips are used in conjunction with light metal ties, the latter are soon rendered useless due to the fact that the clips rapidly wear through the ties. This wearing away of the ties by the clips is especially emphasized in the case of mine ties because of the accumulation of rust between the tie and clip due to dampness of the atmosphere and the like.

In the construction shown in Figures 3 and 4 I employ a conventional type of light weight tie as indicated by the numeral 10, and on the top of this tie at the points where the rails 11 are supported reenforcing plates 12 are mounted. These plates are preferably riveted to the tie and certain of the rivets serve as pivots for the rail securing clips 13 as indicated by numeral 14. In this form of the invention as well as that previously described it will be apparent that I provide, in a light weight and therefore relatively low-priced tie, all of the advantages of the heavier ties in that the tie is properly reenforced at the points receiving the weight of the cars, and in that this reenforcement also serves to prevent destruction of the tie by reason of the action of the rail-securing clips.

In the modified construction shown in Figure 5 I employ a tie 20 provided with down-turned side walls 21 and horizontal flanges 22. With this construction of tie the reenforcing plate takes the form indicated in the cross-sectional view; i. e., the plate 23 is mounted on the top of the tie at the rail supporting position and is provided with flanges 100

24 which overlap and reenforce the side walls 21 of the tie. As in the previously described forms, the plates 23 are secured to the tie by means of the rivets 25 which form the pivots 5 for the clips 5. Obviously, in this embodiment of the invention the advantages of a light weight tie of the particular design shown are secured without the inherent defects, namely, flattening out of the side walls 10 of the tie by excessive weight and wearing away of the tie by the rail clips.

A further modification of the invention is shown in Figure 6, wherein the reenforcing plate 30 is attached to the under side of a tie 31 which is of the same construction as that shown in Figure 4. In this form of the invention the side walls 32 of the tie are reenforced by means of the flanges 33 of the plate 30, and by reason of the reenforcing plate being on the underside of the tie it is possible to provide integral alignment lugs 34 by striking out sections of the metal of the reenforcing plate.

From the foregoing description it will be apparent that I have devised a novel form of mine tie, several modifications of which are shown in the accompanying drawings; that the tie may be made of very light metal and yet be strong and durable in operation; that reenforcement of the tie is so arranged as to not only strengthen the tie at the point of rail support but also to cooperate with the pivoted clips so as to prevent undue wear on the tie by reason of corrosion until the clips become 35 loose and the rail freed from its anchoring means; and that in brief, I provide a tie of light weight and relatively low cost which provides the service and durability of heavier and more expensive ties.

40 In accordance with the patent statutes I have described what I now believe to be the best embodiment of the invention, but I do not wish to be understood thereby as limiting myself or the scope of the invention, as many 45 changes and modifications may be made without departing from the spirit of the invention; all such I aim to include in the scope of the appended claims.

What I claim as new and desire to secure 50 by Letters Patent is:

1. A mine tie formed of light metal, reenforcing plates applied to the upper surface of the tie so as to aid in supporting the rails to be mounted thereon, clips for securing the rails to the tie, and means for securing the plates to the tie and for pivotally mounting the clips on the plates.

2. A mine tie formed of metal tubing, portions of said tubing being collapsed, and reenforcing plates secured to the collapsed portions of the tubing.

3. A mine tie formed of metal tubing, portions of said tubing adjacent the ends thereof being collapsed for the purpose described.

55 JUSTUS J. ROSS.
